DESIGN FOR A WATCH HOLDER

Ellison S. Irelan, Elgin, Ill., assignor to Illinois
Watch Case Company, Elgin, Ill., a corporation of Illinois

Application February 16, 1935, Serial No. 55,472

Term of patent 7 years

To all whom it may concern:

Be it known that I, Ellison S. Irelan, a citizen of the United States, residing at Elgin, in the county of Kane and State of Illinois, have invented a new, original, and ornamental Design for Watch Holders, of which the following is a specification, reference being had to the accompanying drawing, forming part thereof.

Figure 1 is a perspective view of a watch holder showing my new design, and Figure 2 is a side elevational view thereof.

I claim:

The ornamental design for a watch holder, as shown.

ELLISON S. IRELAN.
